CLEANING APPARATUS

Kurt J. Heinicke, Robert Lawrence III, and William J. Langevin, Jr., Hollywood, Fla., assignors to Heinicke Instruments Co., Hollywood, Fla., a corporation of Florida

Filed May 17, 1965, Ser. No. 456,293
6 Claims. (Cl. 239—101)

This invention relates to a washing or cleaning apparatus wherein pressurized fluids are employed to clean trucks, buses, locomotives or the like to effectively remove any deposits or contamination from such items.

The invention comprises a hand held wand for conducting the pressurized elements from a source of pressure to be injected upon the parts of vehicles or the like and with the wand being held by the hand of the operator so as to reach the several relatively inaccessible parts of the vehicle and with the wand having a head portion that is connected to the sources of the several elements, such as water, air and a detergent and with the wand at one end being provided with a nozzle that is adapted to spray the several fluid elements upon the vehicle or the like.

The invention comprises also a wand having a head portion that is connected to a source of water, a source of air and a source of detergent, all being connected to the nozzle and with the source of water being energized in a pulsing action and also the air being injected into a water conducting conduit to impart a pulsing action further to the water prior to its discharge from the nozzle.

Novel features of construction and operation of the device will be more clearly apparent during the course of the following description, reference being had to the accompanying drawings wherein has been illustrated a preferred form of the device and wherein like characters of reference are employed to denote like parts throughout the several figures.

In the drawings:

FIGURE 1 illustrates a side elevation of a wand for 40 application of the invention,

FIGURE 2 is a top plan view thereof,

FIGURE 3 is a fragmentary enlarged sectional view taken substantially on line 3—3 of FIGURE 2,

FIGURE 4 is an enlarged longitudinal sectional view 45 through a spray head taken on line 4—4 of FIGURE 2, and

FIGURE 5 is a diagrammatic illustration of pumping and control means for the several fluids entering the wand.

Referring specifically to the drawings, there has been illustrated a wand as a whole, illustrated at 5. The wand includes a head portion 6 to which is connected a source of water 7. The source of water 7 is provided with a pulsing device shown in U.S. Patent 2,947,312. From an opposite side of the head 6, the water passes to a cylindrical conduit 8' that is intermediately bent at 9 and then extended at 10 to be connected to a nozzle 11. A source of pressurized air conduit 12 passes through the head 6 and enters the conduit 10 and this air is pulsed through a pulsing device 13 in the form of a solenoid valve prior to its entry into the conduit 10 and to create a pulsing action upon the water from the conduit 8. The air supply 12 within the head 6 is also controlled by the solenoid valve 13 and the pulsing device 13 creating an

2

interrupted flow of the air to be mixed with the water in the conduit 10. The end of the air supply pipe 12 is tapered at 15 to effectively impart the pulsing to the water.

As clearly shown in FIGURE 4, the spray head 11 has a shouldered portion 16 that is grooved at 17 upon its discharge side and this shoulder is connected to a conduit 10 leading from the head 6. Also connected to the nozzle 11 is the detergent pipe 18 passes through a bore 19 of the nozzle and then upwardly through a lateral bore 20 to a recess 21 of the nozzle to be mixed with the pulsating water from the conduit 10. A check valve 22, being biased to a closed position by a spring 23 functions to interrupt the flow of the detergent to the surface 21 of the nozzle. The face of the nozzle 11 is forwardly curved to direct an upward spray of the water from the conduit 10 and this spray passing over the lateral bore 20 functions to inject the pressurized detergent upwardly to be mixed with the spray indicated generally at 11'. The nozzle 11 has been illustrated as having a face 21 that is curved upwardly at its outer end however, the face 21 may function just as well by having the face 21 extend entirely to the front end of the nozzle.

As illustrated in FIGURE 5, the head 6 and the several conduits 8, 12 and 18 are controlled by a pump illustrated generally at 24. The pump illustrated at 24 in FIGURE 5 includes a pump rod 25 that is shifted in a back and forth manner by crank arm 26, upon a shaft 27 that is driven from an electric motor 28. The pump rod 25 enters a pump housing 29, having a bore 30 for the reception of the pump rod 25 and the pump receives a source of fluid from an inlet 31. An outlet for the bore 30 is indicated at 32 and disposed within the bore 30 is a pulsing device 33, as in Pat. No. 2,947,312, to impart a pulsing action to the fluid being ejected through the pipe 32, corresponding to the inlet 7 of FIGURES 1, 2, 3 and 5.

Fixed upon the pump rod 25 is a disk 34, having an electromagnet 35 that functions to actuate a switch 36 at each passage of the pump rod beneath the switch housing 37.

Also disposed within the head 6 is the solenoid valve 13. A source of electrical energy 38 is connected to one side of the switch 36 by a conductor 39 and also to the solenoid valve 13 by a conductor 40. The opposite side of the switch 36 is connected to the solenoid valve 13 by a conductor 41. Disposed between the conductors 39 and 41 is a remote controlled switch 42.

While the solenoid valve 13 has been employed to interrupt the flow of air to the conduit 10, it should be understood that any other desirable means may be employed in lieu of solenoid valve 13 such as a mechanical means that is actuated to alternately open and close the air line 12.

In the use of the device, the motor 28 is energized and functions to shift the pump rod 25 back and forth, through the pump housing 29 and to draw the water from a suitable source of supply to the bore 30 when the rod is moved in one direction and to compress and discharge the water through the pulsing device 33 to the conduit 32, leading to the fluid supply pipe 7. After the fluid leaves the pipe 7, it is again subjected to a pulsing action for subsequent discharge through the nozzle 11 at a relatively high pressure and with the pump in operation, the magnet 35 passes back and forth beneath the switch hous-

ing 37, closing and opening the switch 36 that controls the solenoid valve 13, intermittently permitting compressed air to pass through and into the conduit 10 where it again functions to pulse the fluid prior to its discharge from the nozzle 11.

Further, with respect to the washing apparatus, there has been provided a non-flexible wand carrying the various supply pipes from the head 6 and terminating at the nozzle 11. In the water supply pipe 7, there has been injected a pulsating device providing the high frequency pulsating stream and also in the head 6, there has been provided in the air line 12, a pulsating device in the form of a solenoid valve 13 and the pressurized air in pulsating form is injected into the water line 10, increasing the energy level of the liquid stream resulting in a pulse peak pressure greater than the energy level of either the liquid or gaseous medium. When the pulse reaches the nozzle 11, the spray angle is decreased, focusing the high energy liquid on the item being cleaned.

The combination of high frequency and low frequency pulsing spray pattern focusing the results in a cleaning action having a capability many times greater than possibly using a steady stream of liquid pressure. Chemicals, such as detergents may be injected into the spray pattern at the nozzle and the detergent is fed into the high pressure fluid just beyond the point where the solid stream breaks up, resulting in immediate and complete mixing of the detergent with the water. The detergent flow may be controlled at the wand by a button located near the operator's hands and not shown, since the detergent passing through the line 18 is pressurized by a pump, also not shown.

The combination of low frequency and high frequency pulsations in the spray pattern and focusing of the spray pattern with the chemical injection is most effective for the removal of road films, hydrocarbon deposits, diesel oil remnants, rust and scales heretofore not obtainable with existing methods.

It is to be understood that the invention is not limited to the precise construction shown, but that changes are contemplated as readily fall within the spirit of the invention as shall be determined by the scope of the subjoined claims.

We claim:

1. A washing apparatus that includes a rigid wand having a head portion at one end and a spray nozzle at the opposite end, a source of washing fluid extending through the head and connected to the nozzle, a source of pressurized air also extending through the head and into the line of flow of the water and a pressurized detergent extending through the head and terminating at the nozzle, an impulse device located within the water line adjacent its point of passing through the head and an impulse device located within the head and connected to the source of pressurized air whereby to impart a pulsation to the air that is discharged into the water line between the head and the nozzle and means for energizing the second named impulse device within the head.

2. A washing apparatus of the character described comprising a rigid wand having a head portion and a discharge nozzle, a source of water under pressure that passes through the head and connected to the nozzle, a source of pressurized air passing through the head and entering the line of flow of the water from the head to the nozzle, the pressurized air line being provided with an impulse device in the form of a solenoid valve to interrupt the flow of pressurized air at predetermined times and to inject a pulsating flow of pressurized air into the water line from the head portion, a fluid line connected to a source of pressure and passing through the head to the nozzle for conducting a pressurized flow of detergent through the nozzle and an impulse device disposed within the water line prior to its passage through the head whereby to pulsate the water to be further pulsated by the pressurized air and the solenoid valve and means to alter-

nately open and close the solenoid valve to close and open the pressurized air line.

3. The structure according to claim 1 wherein the nozzle is provided with an upper curved face for receiving the pulsating water from the water line and to direct a spray of water or cleaning fluid upwardly at an angle, the detergent line being connected to a lower part of the nozzle and into a bore of the nozzle and with the bore being connected to an upwardly extending lateral bore that communicates with the upper face of the nozzle and whereby fluid from the water line is mixed with the pressurized detergent from the lateral bore as it passes over the face of the nozzle and a check valve disposed within the nozzle for closing the detergent line against feeding of detergent to the spray when pressure upon the detergent line has been interrupted.

4. The structure according to claim 2 wherein a pump is provided to pressurize water that passes through the water line prior to its entrance to the head, the pump having a housing that has a longitudinal bore for the reception of a pump rod, the pump housing and an inlet from a source of water supply to the bore, the first named bore at its discharge and being provided with an impulse generating device for imparting an impulse to the water flowing through the water line, a source of electrical energy that is connected to the solenoid valve of the air line, a switch device disposed in one conductor from the source of electrical energy and a magnetic device fixed to the pump rod that passes back and forth beneath the switch to close and open the switch under the influence of the movement of the pump rod, the switch having conductors connected with the source of energy and the solenoid valve whereby movement of the pump rod causes the switch to open and close to energize and deenergize the solenoid valve whereby the pressurized air is pulsed to be discharged into the water line.

5. A washing device of the character described comprising a rigid wand having a head portion and a discharge nozzle, a source of impaled water adapted to pass through the head and connected to the nozzle, the pulsed water also passing through a pulsation device disposed within the water line, a pressurized source of air passing through the head for terminating in the water line between the head and the nozzle, a solenoid valve disposed within the head and adapted to interrupt the pressurized air prior to its discharge into the water line thereby to further pulse the water being discharged from the nozzle, a source of pressurized detergent passing through the head and connected to the nozzle, the water line being connected to the nozzle and a bore extending through a head portion of the nozzle and a bore extending through a head portion of the nozzle and with the bore upon the face of the head portion of the nozzle being grooved to create a relatively wide spray of water, the nozzle having a curved upper face to direct the spray upwardly at an angle, the detergent line entering a bore of the nozzle and passing through an upwardly extending lateral port whereby the spray of water functions to receive the detergent upwardly to be mixed with the spray and a spring pressed ball valve in the nozzle that closes the detergent line when the detergent is interrupted in its flow, a pump device for pumping water to the water line, the pump device having a pump housing that is provided with a longitudinal bore entirely therethrough and a water inlet to the bore, the pump device including a motor actuated crank and a pump rod having one end slidably in the bore of the pump housing whereby to pull the water from the water supply to the bore of the housing and a discharge pipe from the pump housing that is provided with an impulse generating device and whereby to pulsate the water passing to the water line, the pump rod being provided with a bracket that is movable with the pump rod and with the bracket being provided at its upper end with an electro-magnet, a control switch beneath which the bracket passes and with the switch being closed and

opened by the magnet, the switch being connected to a source of electrical energy at one side and with the solenoid valve from the other side and whereby movement of the pump rod alternately opens and closes the solenoid valve to impart a pulsation action to the air passing through the water line to the nozzle and a remotely controlled switch connected between the conductors leading to the solenoid valve.

5   6. The structure according to claim 2 wherein the pressurized air line entering the water line is provided at its terminal end with a tapered deflector, the several impulse devices serving to pulse the water leading to the nozzle and to also pulse the air from the pressurized air line.
